UNITED STATES PATENT OFFICE.

ALOYS KOCH, OF BERLIN, GERMANY, ASSIGNOR TO THE FIRM OF PERLINER STICK-MASCHINENFABRIK SCHIRMER, BLAU & CO. G. M. B. H., OF BERLIN, GERMANY.

COMBINED GUIDING AND FEEDING DEVICE FOR CRANK EMBROIDERY MACHINES AND THE LIKE.

Application filed February 27, 1925, Serial No. 12,068, and in Germany June 25, 1924.

My invention relates to improvements in combined guiding and feeding devices for crank embroidery machines and the like and the object of the invention is to devise an 5 improved guiding and feeding means which will be free from the disadvantages inherent to the present machines of this type in which the wear and tear on the respective parts is excessive and results in an inaccurate and 10 shaky action of the feeding mechanism.

Hitherto, with crank embroidery, crank hemstitch and sewing machines, it has been customary to provide a feed lever which carries the presser foot and which is suspended 15 from a comparatively high point in such a manner as to be capable of swinging to each side in order to be able to follow the driving pressure of an eccentric. Such point of suspension of the feed lever can be shifted or 20 adjusted vertically in a guide and which comprises a guide bar located on one side of said suspension point with a pivot projecting to one side of the bar and arranged parallelly to the vertical axis of the needle tube.

25 My invention consists in providing an improved guiding device comprising a two sided slide guide, and pivot guide at the supporting block of the feed lever, all as hereinafter more particularly described and 30 illustrated in the accompanying drawing in which:—

Fig. 1 is a front view of one type of crank embroidery machine showing my improvements applied thereto.

35 Fig. 2 is a horizontal section on the line 2—2 Fig. 1.

Fig. 3 is a plan view of my improved means for giving a swinging movement to the feed lever.

40 Fig. 4 is a cross section therethrough.

Fig. 5 is an enlarged horizontal section through the block for supporting the feeder lever.

Fig. 6 is an end view thereof, and

45 Fig. 7 is a perspective view of a modified form of guide member.

Like characters of reference indicate corresponding parts in the different views.

A denotes the frame-plate which is attached to the embroidery machine head and to which the working members are attached in close proximity, said members and their operation being well known in embroidery machines, and form no part of my invention.

The needle cylinder 1, the needle bar tube 2, 55 located therein and the middle tube 3, are supported above in the bearing B and below in the bearing D in order to maintain their vertical position. 4 and 5 are two vertically movable slides, of which 4 is guided by a 60 bracket 7 secured to the frame plate A. The slide 4 can, thus, reciprocate between this plate A and the bracket 7. A forked member 10 extends to the left from the lower end of said slide 4 and engages two collars 11 65 and 12 provided at the upper end of the tube 3, whereby this tube and the slide 4 are coupled with each other. A similar forked member 9 extends to the left from about the middle portion of the slide 5. This slide is 70 guided also between the frame plate A and the bracket 7, but is guided also by a bracket m behind which it extends vertically along the front face of the plate A. Below the bracket 7 the respective end of the slide 5 is 75 located above the slide 4. The forked member 9 engages two collars pertaining to a sleeve 8 surrounding the tube 2, which is, therefore, coupled with the slide 5.

z, Fig. 1 denotes the feed lever which is 80 U-shaped at its lower end g^1 and forked at its upper end g . The lower end receives the presser foot which I have not shown as it does not form a part of the present invention. The fork g is coupled with a block k 85 by screws o' . This block embraces the tube 2 and can be shifted a little along it; the block k is coupled by means of a pivot c (shown in dotted lines in Figs. 1 and 2) with a bracket b projecting forth forwardly from 90 a slide a guided in the top portion of the frame plate A, as well as by a bracket 13. The slide a is continually moved up and down by the machine by the intermediary of suitable members (not shown), and as the 95 lever g^2g^1 is coupled with it, also this lever is moved up and down correspondingly.

In operation the slide a is reciprocated up and down by suitable means acting and disposed at the rear side of the front plate (not shown); since the lever g^2g^1 is operatively connected with the said slide, this lever is moved up and down in unison therewith.

The oscillations on the axis of oscillation $o-o$ and the tilting motion of the pivot c 100 in the bearing b allow, therefore, of a pendulum-motion of the feed-lever z to all sides, whereas the pivot c itself is movable up-

wards and downwards, corresponding to the up and down motion of the slide *a*.

In existing constructions the guide-way of the slide *a* and a one-sided bearing *b*, arranged as described relatively to one another, must stand all strains transmitted to the point of suspension at *o*—*o*, and it has been found that, owing thereto, the guideways concerned are quickly worn out by 10 grinding, and that a positive motion free of shakes of the feed-lever *z* which is actuated in known manner by an eccentric *r* is practically unattainable.

In my construction the pivot pin *c* on the 15 guide block (Fig. 5) is supported in a sleeve *d* in which it is supported somewhat eccentrically, as shown in Fig. 6. The object of this arrangement is to render possible the bringing into agreement the axis of this 20 pivot accurately and centrally with the axis of the vertical bore as well as the guide-way on the other side, whereby the guiding is improved quite considerably and is rendered nearly completely free from wear and tear. 25 By means of the nut *v* which encompasses the slit end of the sleeved bearing *b* the holding device is held in its adjusted position.

Owing to the fact that the auxiliary pivot *c*¹ with its slide member *i* functioning in the 30 guide *m* receives an accurate additional guidance, wear and tear is reduced considerably and a great portion of the strain is done away with. In the event of wear my construction permits the adjusting of the parts 35 without any necessity of providing new blocks.

My eccentric device illustrated separately in Figs. 3 and 4 is characterized by the feature that the ring *r* is designed to form 40 a clamping collar *r'* and is provided with an annular insertion *e* having an outer circumferential groove containing an annular member *f*. It is, by this arrangement and combination of these parts, rendered possible on 45 one hand to adjust accurately the parts concerned in order to permit the insertion *e* to turn freely without binding, and on the other hand to exchange easily the member or ring *f* which serves as an exchangeable bearing for the rotatory insertion and constitutes a member taking up the wear and tear and is replaceable on becoming worn by an accurately fitting new ring.

The sleeve *g* is provided with a sloping guideway disposed laterally thereon and adapted to be engaged by the upper arm of a double armed lever 14, pivoted to the member 15 and extending with its lower arm through a recess near the annular shaped member *e* carried within a ring (Fig. 1).

The said member 15, prismatically shaped at its lower part, also engages a quadrangular opening of the member *e*.

Referring to Fig. 7 which shows a modification of the guideway bracket illustrated in Fig. 2, in this modified form the guideway *w* instead of being formed with integral jaws has an L-shaped part *n* on the one side and a detachable or adjustable part *h* on the other side. The latter can be renewed when the guideway is worn out.

What I claim as my invention is:

1. In a sewing or embroidering machine, the combination with a feed slide, needle holder tube, bearing block therefor, and feed lever connected to the block, of a bracket extending outwardly from the feed slide, and eccentric means for pivotally supporting the block on the bracket so as to be capable of adjustment.

2. In a sewing or embroidering machine, the combination with a feed slide, needle holder tube, bearing block therefor, and feed lever connected to the block, of a bracket extending outwardly from the feed slide and having a horizontally disposed sleeve portion, an eccentrically bored sleeve within the sleeve portion, and a pin secured to the guide block and extending into the bore of the sleeve.

3. In a sewing or embroidering machine, the combination with a feed slide, needle holder tube, guide block therefor, and feed lever connected to the block, of a bracket extending outwardly from the feed slide and having a horizontally disposed sleeve portion, an eccentrically bored sleeve within the sleeve portion, a pin secured to the guide block and extending into the bore of the sleeve, a forked upper end on the feed lever, 100 and pivot pins constituting trunnions extending through the forked end of the feed lever into the block.

4. In a sewing or embroidering machine, the combination with a feed slide, needle holder tube, bearing block therefor, and feed lever connected to the block, of a bracket extending outwardly from the feed slide and having a horizontally disposed sleeve portion, an eccentrically bored sleeve within the sleeve portion, a pin secured to the guide block and extending into the bore of the sleeve and a second pin extending outwardly from the block on the opposite side to the first mentioned pin, a slide member, said second pin extending into a hole in the slide member.

In testimony whereof I affix my signature.

ALOYS KOCH.
